United States Patent Office

Des. 186,472
Patented Oct. 27, 1959

186,472

BOTTLE

Ray J. Wunderly, Glenshaw, Pa., assignor to National Cordial Company, Chicago, Ill., a corporation of Illinois

Application May 27, 1958, Serial No. 51,093

Term of patent 14 years

(Cl. D58—6)

I claim:

The ornamental design for a bottle, as shown.
